IRONING APPARATUS HAVING A MOVABLE
CLOTHES PANWilliam A. Johnston, Mansfield, Ohio, assignor to
Westinghouse Electric Corporation, East Pitts-
burgh, Pa., a corporation of Pennsylvania

Application April 1, 1947, Serial No. 738,515

8 Claims. (Cl. 38—61)

1

My invention relates to apparatus for ironing fabrics and has for an object to provide improved apparatus of this kind.

A further object of the invention is to provide, in an ironer of the domestic type having a padded rotatable roll and a heated shoe, movement of the ironed fabrics toward the operator at the conclusion of an ironing operation, whereby the removal of the finished fabrics from the machine is facilitated.

A further object of the invention is to provide an improved safety release mechanism for an ironer of the type set forth, which is readily accessible to the operator at the front side of the machine.

In practicing the invention, I provide a movable tray member disposed beneath the roll of an ironing machine having a conventional padded roll, a heated shoe and a driving mechanism for rotating the roll and for moving the roll and shoe into and out of ironing engagement. The tray is disposed to receive the ironed fabrics as they descend from between the roll and shoe. When the shoe and roll are disengaged at the conclusion of an ironing operation, the driving mechanism moves the tray toward the operator whereby the ironed fabrics may be conveniently removed from the tray. The tray is mechanically connected to said driving mechanism and may be manually actuated by the operator relative thereto in order to rapidly disengage the shoe and roll independently of the driving mechanism. Preferably, a toggle mechanism or its equivalent defines a driving connection between the driving mechanism and the shoe and this toggle mechanism is connected to the tray. Normally, the toggle mechanism reciprocates the tray as the shoe is moved by the driving mechanism but, when the operator manually moves the tray, the toggle is broken and the shoe rapidly moves out of engagement with the roll independently of the driving mechanism. The operator's hands are usually adjacent the tray, so that, in an emergency, this member may be readily actuated to rapidly disconnect the shoe and roll.

These and other objects are effected by my invention as will be apparent from the following description and claims taken in connection with the accompanying drawings, forming a part of this application, in which:

Fig. 1 is a front view in elevation of an ironing machine constructed and arranged in accordance with my invention;

Fig. 2 is a view in section taken along the line II—II of Fig. 1;

Fig. 3 is a view in section taken along the line III—III of Fig. 2;

Fig. 4 is a view in perspective of a detail shown in Figs. 1 to 3, inclusive;

Fig. 5 is a rear view of the machine; and

2

Fig. 6 is a view similar to Fig. 2, showing the shoe of the machine in a different position.

Referring now to the drawings, I have elected to disclose my invention applied to a domestic ironing machine of the type including a rotatable padded roll 10 and a heated shoe 11 cooperating therewith. The roll is rotated by a shaft 12 and the shoe 11 is oscillated into and out of engagement with the roll 10 by an oscillating shaft 13. 10 A domestic ironer of this type is shown, for example, in U. S. Patent No. 2,254,166, granted August 26, 1941. The shoe 11 includes an arcuate ironing plate 14 which is heated by a suitable electric heating element 15, the latter being 15 clamped against the ironing plate 14 by a backing plate 16. The shoe 11 is supported by a relatively heavy leaf spring 17, the opposite ends of which are slidably connected to a pair of bosses 18 carried by the backing plate 16. As shown, 20 the leaf spring 17 is provided with elongated openings 19 through which bolts 21 are passed, which bolts 21 are threaded in the bosses 18. The elongated openings 19 provide for relative movement between the ends of the spring 17 and the bosses 18 when the shoe 11 is forced into 25 engagement with the roll. At this time it will be understood the spring 17 is stressed.

The shoe 11 is supported by a pair of arms 22 which are loosely fitted upon the shaft 13 and 30 which are provided at their upper ends with a pin 23. The pin 23 extends through a boss 24 fixed in any well-understood manner to the center portion of the spring 17. It will be understood that the roll and shoe which I have shown 35 are disclosed by way of example and that other suitable roll and shoe constructions may be employed.

The shafts 12 and 13 are actuated by a driving mechanism indicated at 25, which may be of any well-understood construction and, since the 40 mechanism 25 per se forms no part of the present invention, it has not been shown in detail for the sake of brevity. A suitable driving mechanism of the type shown at 25 is disclosed in 45 the aforementioned Patent No. 2,254,166. It will be understood, however, that the driving mechanism 25 may be adjusted by the operator of the machine to initiate and terminate rotation of the roll and to actuate the shoe 11 into and out 50 of engagement with the roll. The driving mechanism 25 is carried by a table or base 26, the latter also supporting a bearing 27 for the outer end of the oscillating shaft 13.

In accordance with my invention, a tray 28 55 is slidably supported by the table 26 so that it may move beneath and transversely of the roll 10. The tray 28 is disposed to receive the ironed fabrics as they drop from between the roll and shoe during an ironing operation. At the conclusion of the ironing operation when the shoe 60 11 is being disengaged from the roll 10, the tray

28 is moved forwardly toward the operator of the machine or, as viewed in Figure 2, to the left. Accordingly, the ironed fabrics which have gathered in the tray 28 are moved toward the operator to facilitate the removal of the fabrics from the machine. As described hereinafter, the tray 28 may also be moved manually by the operator to actuate the shoe 11 to its open position or the position wherein it is disengaged from the roll 10. A handle structure 29 may be formed along the front side of the tray for manually moving the same forwardly. It will be understood that the tray 28 is manually actuated in an emergency in order to rapidly disengage the roll and shoe. The mechanism for sliding the tray 28, as described, and for rapidly disengaging the roll and shoe will now be described.

As set forth heretofore, the arms 22 are loosely carried by the shaft 13 so that they may move relative the shaft 13. The arms 22 are connected to the shaft 13 so that they are oscillated therewith by a toggle mechanism, generally indicated at 31 and including a link 32 pivoted at one end, as shown at 33, to the arms 22. A second bifurcated link 33, shown in detail in Figure 4, is pivoted as shown at 34 to the outer end of an arm 35, the latter being keyed, as shown at 36, to the shaft 13 intermediate the arms 22. The opposite ends of the links 32 and 33 are pinned together, as shown at 37, and therefore define a toggle mechanism connecting the shaft 13 and the shoe supporting arms 22. As best shown in Figure 2, the links 32 and 33 are biased upwardly into engagement with a stop 38 by a light tension spring 39, the latter being suitably supported by the arms 22.

In the position of the apparatus shown in Figure 2, the center of the pin 37 is slightly above a line intersecting the centers of the pins 30 and 34 so that, the links 32 and 33, in this position, provide a driving connection between the shaft 13 and the arms 22 for engaging and disengaging the shoe 11 and the roll 10.

In order to actuate the tray 28 as described, a finger 41 projecting downwardly from the link 33 is disposed in an opening or slot 42 formed in a tongue 43 extending rearwardly from and fixed to the tray 28. The apparatus as shown in Figure 2 is in the ironing position and at this time, fabrics, as they pass from between the roll and shoe, gather in the tray 28 beneath the roll 10. When the operator adjusts the driving mechanism to disengage the shoe at the end of the ironing operation, the shaft 13 is moved angularly in clockwise direction and, through the toggle mechanism 31, moves the arms 22 and shoe 11 to the open position of the latter. During this movement the finger 41 moves the tray 28 forwardly toward the operator in order that the fabrics may be more readily removed from the tray. When the driving mechanism is adjusted to close the shoe and roll, the finger 41 is moved counterclockwise to retract the tray 28 to the position shown in Figure 2. It will be understood that, the arms 22 acting through the leaf spring 17 impart sufficient pressure to the shoe to carry out the ironing operation.

In the event of any emergency when it is desirable to rapidly disengage the shoe and roll, the toggle 31 is broken, as shown in Figure 6, so that the stressed spring 17 rapidly actuates the shoe 11 and the arms 22 away from the roll to the position shown in Figure 6. At this time, of course, the arms 22 move relative the shaft 13. The breaking of the toggle 31 is effected by

manually moving the tray forward. This movement swings the finger 41 clockwise about the pin 34 and, after the pin 37 has passed over center, the heavy spring 17 which, at this time is stressed, rapidly forces the arms 22 clockwise about the shaft 13 and the inertia of the arms 22 and the shoe 11 carry the apparatus to the position shown in Figure 6.

It will be understood that the spring 39 has insufficient force to close the toggle 31 after it has been broken and while the oscillating shaft 13 is in the position shown in Figure 6. The construction and arrangement is such, however, that when the operator moves the tray 28 rearwardly or to the right, as shown in Figure 6, the finger 41 will be moved counterclockwise in order to actuate the links 32 and 33 toward their aligned position, after which the tension spring 39 will move the links 32 and 33 to their over-center position in engagement with the stop 38, as shown in Figure 2. Another way to actuate the links to their active position, as shown in Figure 2, would be for the operator to adjust the driving mechanism 25 to move the shaft 13 clockwise to its "shoe open" position. It will be apparent from Figure 6 that as the shaft 13 is so actuated it would move the links 32 and 33 toward their aligned position, after which the spring 39 moves the links into engagement with the stop 38.

From the foregoing description, it will be apparent that I have provided an improved domestic ironer having provisions for collecting the ironed fabrics beneath the roll and, at the conclusion of an ironing operation, for moving the fabrics forwardly from beneath the roll to a region where their removal from the machine is facilitated. The movable tray in which the fabrics are collected is employed as an operating member to rapidly disengage the shoe and roll in an emergency. Fast emergency operation is facilitated as the operator's hands are adjacent the tray during ironing operations. My invention may be readily applied to conventional ironers with little change in the construction of such ironers. It is understood that the disconnectible shoe-operating toggle structure which I have shown is disclosed by way of example and that my invention is applicable equally well to ironers having other disconnectible shoe-actuating mechanisms.

While I have shown my invention in but one form, it will be obvious to those skilled in the art that it is not so limited, but is susceptible of various changes and modifications without departing from the spirit thereof.

What I claim is:

1. In an ironing machine having a pair of cooperating ironing elements, one of which is a roll and the other of which is a shoe, the combination of driving means for rotating said roll and for actuating the shoe into and out of engagement with the roll, a tray disposed below the roll for receiving ironed fabrics as they pass from between the roll and shoe, a support for slidably carrying the tray, means responsive to movement of the tray into and out of engagement with the roll for, respectively, sliding the tray away from and toward the operator of the machine, said tray being also manually slidable on said support, and means responsive to manual movement of the tray upon its support for rapidly actuating said shoe out of engagement with the roll independently of the driving means.

2. In a machine for ironing fabrics including

a padded roll and a heated shoe engageable therewith, a driving mechanism for rotating said roll and a shaft oscillated by the driving mechanism for actuating the shoe into and out of engagement with the roll, the combination of bracket supporting the shoe and loosely mounted upon said shaft, a toggle mechanism connecting the shaft to the bracket and defining a driving connection therebetween, a tray disposed beneath said roll for receiving ironed articles as they pass from between the roll and shoe, means for slidably supporting the tray, a member associated with said toggle mechanism and engaging the tray for moving the tray toward and away from the operator of the machine when said shoe is actuated, respectively, out of and into engagement with the roll, said tray and said member being also manually movable to break the toggle mechanism and to effect rapid movement of said bracket and shoe away from said roll independently of the shoe actuating shaft.

3. In a machine for ironing fabrics including a padded roll and a heated shoe engageable therewith, a driving mechanism for rotating said roll and a shaft oscillated by the driving mechanism for actuating the shoe into and out of engagement with the roll, the combination of a bracket supporting the shoe and loosely mounted upon said shaft, a toggle mechanism connecting the shaft to the bracket and defining a driving connection therebetween, a tray disposed beneath said roll for receiving ironed articles as they pass from between the roll and shoe, means for slidably supporting the tray, a member associated with said toggle mechanism and engaging the tray, means responsive to manual movement of the tray for actuating said member to break said toggle mechanism, and biasing means for effecting rapid movement of said bracket and shoe away from the roll independently of the shoe-actuating shaft.

4. In a machine for ironing fabrics including a padded roll, a heated shoe engageable therewith, a driving mechanism for rotating said roll and a shaft oscillated by the driving mechanism for actuating the shoe into and out of engagement with the roll, the combination of an arm supporting the shoe and loosely mounted upon said shaft, a disconnectible mechanism connecting the shaft to said arm and defining a driving connection there-between, a tray disposed beneath said roll for receiving ironed articles as they descend from between the roll and shoe, means for movably supporting the tray, and means connecting said tray and said connecting mechanism and operable in response to manual movement of the tray for disconnecting the connecting mechanism and biasing means for rapidly moving said arm and shoe away from said roll.

5. In an ironing machine, the combination of a pair of cooperating ironing elements, a driving mechanism for engaging and disengaging the ironing elements, a tray arranged beneath the ironing elements for receiving ironed articles as they descend from between the ironing elements, means for movably supporting say tray, a member reciprocated by the driving mechanism and means connecting said member and tray for moving the tray forwardly and rearwardly of the ironing machine as the ironing elements are disengaged and engaged, respectively.

6. In an ironing machine having a pair of cooperating ironing elements, one of which is a rotatable padded roll and the other of which is a

- heated shoe, the combination of driving means for rotating the roll and for actuating one of said ironing elements toward and away from the other, manually-actuated means for controlling operation of the driving means, a tray disposed beneath the roll and shoe for receiving ironed articles as they descend from between the roll and the shoe, a support for movably supporting said tray, emergency release means connecting said driving means and said one ironing element and including a member movable with said one ironing element and also relative thereto for actuating the emergency release means, and means connecting the tray and said member for moving the latter relative to said one ironing element for the actuation of the emergency release means in response to manual movement of said tray upon its support.
7. In an ironing machine having a pair of cooperating ironing elements, one of which is a roll and the other of which is a shoe, the combination of driving means for rotating the roll and for actuating one of said elements toward and away from the other, a tray disposed beneath the roll and shoe for receiving ironed articles as they drop from between the roll and shoe, a support for slidably supporting said tray, a member reciprocated by the driving mechanism and movable with said one ironing element, and means connecting the tray and said member for reciprocating the tray, said tray being actuated by the member transversely with respect to the roll in response to movement of said one ironing element.
8. In an ironing machine having a pair of cooperating ironing elements, one of which is a rotatable padded roll and the other of which is a heated shoe, the combination of driving means for rotating the roll and for actuating one of said ironing elements toward and away from the other, manually-actuated means for controlling operation of the driving means, a tray disposed beneath the roll and shoe for receiving ironed articles as they descend from between the roll and the shoe, a support for movably supporting said tray, emergency release means connecting said driving means and said one ironing element and including a member movable with said one ironing member and also relative thereto for actuating the emergency release means and means connecting the tray and said member, said connecting means being effective to move the tray transversely with respect to and beneath the roll in response to movement of said one ironing element and said member, and said connecting means being effective to move the member relative said one ironing element for the actuation of the emergency release means in response to manual movement of the tray upon its support.
